(57) **CLAIM**

The ornamental design for mosquito net pants, as shown and described.

DESCRIPTION

FIG. 1 is a front perspective view of mosquito net pants showing my new design;

FIG. 2 is a front elevational view thereof;

FIG. 3 is a left side elevational view thereof, the undisclosed right side elevational view being a mirror image; and,

FIG. 4 is a rear elevational view thereof.

In the drawings, the broken lines represent stitching forming part of the claimed design.
